The ornamental design for an electrode bar for an optical fiber fusion splicer, as shown and described.

DESCRIPTION

FIG. 1 is a front view of a electrode bar for an optical fiber fusion splicer of the present invention.

FIG. 2 is a rear view of the electrode bar for an optical fiber fusion splicer of FIG. 1.

FIG. 3 is a top plan view of the electrode bar for an optical fiber fusion splicer of FIG. 1.

FIG. 4 is a bottom plan view of the electrode bar for an optical fiber fusion splicer of FIG. 1.

FIG. 5 is a right side view of the electrode bar for an optical fiber fusion splicer of FIG. 1.

FIG. 6 is a left side view of the electrode bar for an optical fiber fusion splicer of FIG. 1.

FIG. 7 is a perspective view from above of the electrode bar for an optical fiber fusion splicer of FIG. 1; and,

FIG. 8 is a rear perspective view from below of the electrode bar for an optical fiber fusion splicer of FIG. 1.
